DESIGN FOR A GLOVE

Norman Blum, New York, N. Y.

Application May 20, 1938, Serial No. 77,316

Term of patent 3½ years

To all whom it may concern:

Be it known that I, Norman Blum, a citizen of the United States of America, residing in the city of New York, State of New York, have invented a new, original, and ornamental Design for a Glove, of which the following is a specification, reference being had to the accompanying drawing, forming part thereof, wherein,

Figure 1 is a perspective view showing the rear side of a glove embodying my new design, and

Figure 2 is a like view showing the front side of the same.

The essential feature of my design resides in the triangular cut thumb flap in combination with the specific glove.

I claim:

The ornamental design for a glove, substantially as shown and described.

NORMAN BLUM.
